AXEL BREMBERG AND ALEXANDER BANKS, OF GLASGOW, SCOTLAND.

RECOIL APPARATUS FOR ORDNANCE.

1,385,301.

Specification of Letters Patent. Patented July 19, 1921.

Application filed June 17, 1920. Serial No. 389,737.

(GRANTED UNDER THE PROVISIONS OF THE ACT OF MARCH 3, 1921, 41 STAT. L., 1313.)

To all whom it may concern:

Be it known that we, AXEL BREMBERG and ALEXANDER BANKS, of Parkhead Forge Rolling Mills and Steel Works, in the city and county of Glasgow, Scotland, engineers, have invented certain new and useful Improvements in Connection with Recoil Apparatus for Ordnance, of which the following is the specification.

10 The invention relates to that type of recoil apparatus for ordnance in which there is a hydraulic buffer and an air recuperator; that is to say, in which the force of recoil is applied to a hydraulic piston operating in a cylinder from which cylinder liquid is thereby moved to one side of a floating piston in a second cylinder, the other side of which compresses air in that cylinder and in a supplementary cylinder or vessel (any 15 or all of which parts may be in duplicate or more) while expansion of the air so compressed returns the gun to firing position.

The invention has primarily for its object to provide in such apparatus improved 20 and simple means for adjustably controlling the speed of flow of liquid from the first to the second cylinder and so for controlling the resistance against recoil. The invention has further for its object to provide simple 25 means for recharging the apparatus with liquid and for indicating the conditions within the apparatus. Further, there is combined with the means for closing the aperture by which the apparatus is charged 30 means for indicating to the operator when it is safe to use the gun—it being unsafe to do so when there is an insufficiency of liquid (that insufficiency being indicated by a fall 35 of pressure in the liquid) or when the air pressure falls.

According to the invention the joint means for adjustably controlling the speed of flow from the first to the second recoil cylinder and for recharging the apparatus with liquid 40 and indicating the conditions within it comprise a plug closing the end of the second cylinder and having within it a chamber always communicating with the first cylinder, a valve controlling communication between 45 that chamber and the second cylinder and carried on a spindle extending outward through a stuffing box and of such length that it may be moved inward so as to arrest the usual floating piston in the second cylinder,

der and a normally closed aperture for filling purposes communicating with the interior of the second cylinder.

An example of the carrying out of the invention is illustrated in an accompanying sheet of explanatory drawings, Figure 1 being a longitudinal section of that part of the recoil gear to which the invention relates, and Fig. 2 an enlarged sectional elevation of a detail, while Figs. 3 and 4 are respectively a sectional side elevation and an end elevation of the improved indicating device.

In carrying out the invention the rear end of the second cylinder A—that in which the floating piston B operates—is closed by a plug C. Around this plug is a groove, forming between the plug and the wall of the cylinder an annular chamber C¹. This annular chamber communicates firstly with a passage C² from the space before the advancing piston in the first and hydraulic cylinder (not shown). Secondly the annular chamber C¹ communicates by way of a series of ports D with a valve seat D¹ formed upon the inner face of the plug. With this valve seat D¹ there coacts a valve E of conical mushroom form carried on a spindle E¹ passing out rearwardly through the plug C and of such a length that for a purpose hereinafter explained its inner end may be caused to project a considerable distance within the cylinder. The spindle is screwed and engages a counterpart thread in the plug C after the usual manner of a screw-down valve, and is provided at its outer extremity with a removable handle E². By operation of this handle the effective area of the ports D connecting the annular chamber C¹ with the valve seat D¹ may be varied, thus varying the area of communication between the first and second cylinders of the apparatus and thus varying the resistance against recoil.

As more clearly seen in Fig. 2, there is provided a stepped part E³ on the valve which just comes into contact with the valve seat D¹ and thus prevents complete closure of the ports D communicating with the annular chamber C¹.

A port G connects the annular chamber (by way of the port G and passage C²) with a filling orifice G¹ (Fig. 3) normally closed by a plug G². In order to make up for leakage of liquid from or within the cylinder,

the valve spindle E¹ can be operated to move inward beyond what is necessary for adjusting the recoil. The inner end of the valve spindle will thus encounter and force back 5 the floating piston B until the valve spindle E¹ is retained by the engagement of a shoulder E⁴ on it with the end of a counterbore C⁴ in the plug. This relieves the liquid from the air pressure acting on the front side of 10 the floating piston. The filling plug G² may then be removed. After the required quantity of liquid has been inserted and the plug replaced, the valve spindle E¹ is moved away from the floating piston B and the 15 valve E brought to its operative position.

As it is only safe to fire the gun when a sufficient pressure exists in the air reservoir, and as this air pressure sets up an identical pressure in the liquid until the leakage has 20 passed a certain safe limit, a pressure gage or indicator is provided in the filling plug G² itself. This plug indicator which is so placed that it is under the operator's eye and shows at a glance whether the gun can be 25 fired or not, consists of a pressure gage of that well-known form comprising a tube H closed at one end, open at the other and curved in annular form. The closed free end of this tube H is as usual connected by 30 multiplying gearing H¹ with a pointer H² visible through a glazed aperture H³ in the top of the plug G² and reading upon an index mark H⁴. The aperture H³ is of but small angular width, and there may be ar- 35 ranged behind the pointer a backing of luminous material, or alternatively the pointer may be coated with luminous material.

Since at the moment of recoil the pressure 40 gage is subjected to very intense pressure, it is necessary that its tube should be protected from undue distortion or fracture due there- 45 to. For this reason, the gage tube is en- circled by a seating G³ in the plug of such dimensions that when the tube has expanded to a pressure slightly above that indicative of proper working conditions, its outer periphery comes to rest against the seating, and further and possibly damaging distortion is 50 prevented thereby.

What we claim is:

1. A recoil apparatus for ordnance, comprising a cylinder, a floating piston therein subjected on one face to air pressure and on 55 its other face to a pressure liquid, a plug closing the liquid entry end of the cylinder, but affording a chamber communicating

with the liquid inlet port, passage means be- 60 tween said chamber and the cylinder, a valve controlling said passage, means for displac- 65 ing said valve into engagement with the floating piston to support the latter against the air pressure thereon, and a normally closed liquid fill port communicating with the cylinder.

2. A recoil apparatus for ordnance, comprising a cylinder, a floating piston therein subjected on one face to air pressure, and on its other face to pressure liquid, a plug closing the liquid entry end of the cylinder, 70 but having an annular recess forming with the cylinder an annular chamber surround- 75 ing the plug, an inlet port communicating with said chamber, a passage establishing communication between said chamber and cylinder, a valve controlling said passage, means for displacing said valve into en- 80 gagement with the floating piston to support the latter against the air pressure thereon, and a normally closed liquid fill port com- 85 municating with the cylinder.

3. A recoil apparatus for ordnance, comprising a cylinder, a floating piston therein subjected on one face to air pressure, and on its other face to pressure liquid, a plug closing the liquid inlet end of the cylinder, 90 but affording a chamber communicating with the liquid inlet port, passage means be- 95 tween the said chamber and the cylinder, a valve controlling said passage, means for preventing complete closure of said passage by said valve, means for displacing said valve into engagement with the floating piston to support the latter against the air pressure thereon, and a normally closed liquid fill port communicating with the cylinder.

4. A recoil apparatus for ordnance, comprising a cylinder, a floating piston therein subjected on one face to air pressure, and on its other face to a pressure liquid, a plug closing the pressure liquid end of the cylinder, but affording a passageway through 100 which said pressure liquid may pass, a valve controlling said passageway, and a valve 105 stem passing through said plug and displaceable into engagement with the floating piston to support the latter against the air pressure thereon.

In testimony whereof we have signed our 110 names to this specification.

AXEL BREMBERG.
ALEXANDER BANKS.
